 tion of Switzerland

Application February 10, 1942, Serial No. 430,290
 In Switzerland April 10, 1941

10 Claims. (Cl. 290—38)

The present invention relates to a starting device for internal combustion engines having a starting motor and a pinion driven by said motor, said pinion being axially displaceable for engaging a gear ring of the engine.

In starting devices of this kind the teeth of the axially displaceable pinion will engage the tooth gaps of the gear ring only when the pinion has attained certain angular positions on reaching said ring. In most cases, the pinion will have to be turned in order to mesh with the gear ring. For this purpose, in the devices heretofore known, the starting motor is driven forwards or backwards with full or reduced torque, while the pinion is axially pressed by a spring against the gear ring to be brought into engagement with the same as soon as it attains a suitable angular position. The pinion remains in such positions only during a very short period of time so that a spring of considerable strength is required to bring it timely into engagement. But this considerable axial pressure of the pinion against the gear ring very often results in an undesirable wear of the front faces of these parts.

The object of this invention is to provide means for bringing the pinion into engagement with the gear ring without starting the motor, the pinion being only displaceable against a small resistance. In the case of a greater resistance, the attempt to bring the pinion into engagement shall be vain, and on giving up the attempt, the pinion shall automatically attain an angular position differing from the one in which it was before starting this attempt so as to give a possibility of success for the following attempt.

According to the invention, the pinion is coupled for rotation with an axially displaceable pinion carrier and axially slideable relative thereto against a force which is effective in the engaging direction and tending to press said pinion against an abutment on the pinion carrier, a non-displaceable or only limited axially displaceable intermediate member being provided in the driving connection between the pinion carrier and the rotor of the starting motor, which member is coupled to said rotor by an overrunning clutch enabling the intermediate member to advance relative to said rotor in the operative direction of rotation of the same, and to the pinion carrier by a steep-pitch thread by means of which said member is turned in the said operative direction with respect to the pinion carrier when the latter is axially displaced in engaging direction with respect to the intermediate member.

Preferably, displacement of the pinion with

respect to the pinion carrier is limited in both, the engaging and disengaging direction by suitable abutments. The operating device of the starting motor can then appropriately be made dependent upon the movement of the pinion carrier in such a way as to permit of starting said motor only when the pinion carrier has attained a position in which the entire axial displacement of the pinion with respect to the pinion carrier causes said pinion to engage the gear ring with at least a part of its tooth breadth.

For axially displacing the pinion carrier, the starting device may comprise a shifting member adapted to transmit to the pinion carrier forces which are only effective in the engaging direction along that portion of the path of the pinion carrier through which the latter has to travel from its resting position to a position wherein the pinion engages the gear ring with a part of its tooth breadth. The switching device of the starting motor may be operable by the said shifting member.

In the accompanying drawings an embodiment of the invention is represented by way of example.

Fig. 1 is a longitudinal sectional view of a starting device taken on the line A—A of Fig. 2.

Fig. 2 is a cross sectional view of the same starting device taken on the line B—B in Fig. 1.

Figs. 3 to 7 show essential parts of the device according to Figs. 1 and 2 in different operating positions.

The casing of the starter is composed of three main parts, i. e. the bearing plate 1, the field-winding carrier 2 and the switch housing 3, which are firmly held together by longitudinal bolts or screws not shown. The rotor of the starting motor has a hollow shaft 4, one end of which is journaled on a pin-like extension 5 of the switch housing 3, while its other end is widened out to form a clutch casing 6 which is fixed in any known manner to an end plate 7 supported in the bearing plate 1.

The rotor shaft 4 carries the laminated armature core 8 having thereon the armature winding 9, and the commutator 10. On the surface of the latter slide the carbon brushes 13 and 14 guided in brush holders 11 and 12; the brush holders are mounted on a partition 15 of the switch housing 3, which partition is shown separating the starting motor from the switch described farther down. The brush holder 11 and brush 13 are insulated with respect to the switch housing 3, while the brush holder 12 and brush 14 are earthed across the housing 3. In the field-winding carrier 2 are fixedly mounted iron pole

pieces 11 by means of screws 16, and each pole piece carries a field winding 18 wound thereon.

In the switch housing 3 a magnet coil 19 is located in which an iron core 20 is longitudinally displaceable. The latter carries a plate 21 on which a leaf spring 22 is fixed by means of rivets 23; the spring 22 is insulated from the plate 21 by a non-conductive intermediate layer 27 and from the rivets 23 by insulating bushes and washers 28. On the ends of said spring, contact blocks 24 and 25 are located which cooperate with contacts 26 and 27 insulatedly fixed to the housing 3. The contact 26 is connected to the positive pole of a source of current by means of a cable 29 and a terminal post 28 which is likewise insulated from the housing 3. To the contact 27 is riveted a strip 30 which extends through a hole in the partition 15 to be connected to one end of the field winding of the starting motor.

The latter is a direct current series wound motor. When the magnet coil 19 is excited and, by the effect of its attractive force on the core 20, presses the contact blocks 24 and 25 against the contacts 26 and 27, respectively, the current flows from the positive pole of the source of current through the cable 29, the terminal post 28, the pair of contacts 26/24, the spring 22 and the pair of contacts 25/27 to the connecting strip 30. From the latter the current will pass through a conductor 31 to the field winding, the coils 18 of which are connected to one another by a conductor indicated by 32. The other end of the field winding is connected by a conductor 33 to the insulated brush 13 which transmits the current across the commutator 10 to the armature winding 9. The brush 14 collecting the current on the opposite side of the commutator is earthed; also the negative pole of the source of current must be earthed in this case so that the return of the current is established by earth. The brush 14 might just as well be connected to the negative pole of the source of current by a separate conductor.

In the hollow rotor shaft 4 and in a likewise hollow journal 34 of the end plate 7 of the clutch casing are rotatably lodged two bushes 37 and 38 between a shoulder 35 of the bore in the shaft and the inner end face 36 of the bearing plate 1, limiting the bearing of the journal 34; the said bushes are arranged adjacent each other with a slight longitudinal play so as to be axially displaceable in close limits only. The front bush 37 which abuts the bearing plate 1 has a smooth cylindrical outer surface and presents on the inside a steep quadruple square thread which extends over the whole length of said bush.

Between the end plate 7 and a bottom 39 of the clutch casing 6 a ring 40 is supported on the bush 37 which is freely rotatable on said bush. Said ring has on its inner working surface, parallel to the axis, several grooves 41, of which the depth of each increases in the operative direction of rotation of the rotor of the starting motor. In the present example, this operative direction is supposed to be clockwise as indicated by the arrow 42 in Fig. 2 when the starting motor in Fig. 1 is viewed from the right-hand side. In each one of the grooves 41 lies a steel roller 43. Upon turning the ring 40 relative to the bush 37 in the operative direction 42, the rollers 43 roll into the part of little depth of the grooves 41 so as to become jammed between the working surface of the bush 37 and the bottom of the grooves, whereby by reason of the friction produced between these surfaces and the rollers torques are

transmitted from the ring 40 to the bush 37. On the other hand, when the bush 37 is turned to advance relative to the ring 40 in the operative direction 42, the rollers 43 roll into the deeper part of the grooves 41 to rest therein without exerting any pressure on the working surface of the bush 37 and the bottom of the grooves. The rollers then transmit no torque between these surfaces, and the bush 37 is free to advance with respect to the ring 40 in the direction 42.

On the outer surface of the ring 40 and the inner surface of the wall of the clutch casing 6 are provided, parallel to the axis, grooves 44 and 45, respectively, of rectangular cross section. In the clutch casing, between the surfaces mentioned, are disposed several sets of ring shaped friction discs. In each of these sets a steel disc 46, having on its circumference projections 47 which engage the grooves 45 of the casing, is followed by a disc 48 devoid of projections and made of brake covering material (called Ferodo), then by a steel disc 49 having on its inner border projections 50 which engage the grooves 44 of the ring 40, and finally by another Ferodo-disc 48. On the latter bears the first steel disc 46 of the following set and so on. On the side of the end plate 7 of the clutch casing 6, these sets of friction discs are followed by a solid ring 51 of trapezoidal cross section having its thickest portion on the inner border, and finally, there are provided two adjacent conical pressure discs 52 whose inner borders bear against the inner border of the ring 51 while the outer borders of said discs rest on a shoulder 53 of the end plate 7. These pressure discs are so shaped as to become deformed on assembling the end plate 7 with the clutch casing 6 thus pressing by the intermediary of the ring 51 the friction discs 46, 48 and 49 against one another with a certain force.

Owing to the friction between these discs, a certain torque is transmitted from the clutch casing 6, coupled for rotation with the discs 46 by the engagement of the grooves 45 and projections 47, to the ring 40 which is connected to the discs 49 by the grooves 44 and projections 50. If, on the other hand, the torque to be transmitted increases, the friction discs 46, 48 and 49 begin to slide relative to each other so that the effective torque imparted to the bush 37 can in no case exceed a certain value.

In the bushes 37 and 38 is arranged a sleeve 54 forming a part of a pinion carrier, the whole of which is designated by the numeral 55. The sleeve 54 is provided on the outside over a part of its length with a steep pitch thread 56 corresponding to and engaging the female square thread of the bush 37. The direction of the helix of this steep pitch thread is such that upon displacing the pinion carrier 55 to the right in Fig. 1 of the drawings the bush is turned in the operative direction 42 (Fig. 2) with respect to said pinion carrier. The inside of the sleeve 54 forms a guide for the shank 57 of a pinion 58 which shank is formed integral with said pinion and provided with splines 59 extending parallel to the axis and engaging corresponding grooves on the inside of said sleeve; the pinion 58 is thus coupled for rotation with the pinion carrier 55 but can slide axially with respect to the same.

The pinion carrier 55 is formed, on the one side with a spindle 60 extending through a longitudinal bore in the pinion 58 and the shank 57. The free end of said spindle carries an abutting nut 61 screwed thereon and secured by a pin 62. Between the bottom 63 of the pinion carrier 55

and the front face 64 of the pinion shank 57 is interposed a relatively weak compression spring 65 tending to press the pinion against the abutting nut 61. The stroke of the pinion against the pressure of the spring 65 is limited by a shoulder 66 on the spindle 60.

On the other side, the pinion carrier 55 is formed with a shank 67 to which a spring plate 68 is secured. Upon said spring plate rests one end of a compression spring 69 bearing with its other end on the bottom 70 of the bush 38 and tending to shift the pinion carrier inwards, that is to the left in Fig. 1. The inward movement of the pinion carrier is limited by its bottom 68 abutting the front face of the bottom 70 of the bush 38, and the outward movement is limited by the spring plate 68 abutting the back face of said bottom.

The iron core 20 of the switch forms the shifting member controlling the operating means of the pinion of the starting device. The said core is provided with a peg 71 guided in an axial bore of the pin-like extension 5 of the switch housing 3. The front face 12 of said peg lies in the path of the end face 13 of the shank 67 of the pinion carrier. The length of the peg 71 is such that the switch cannot be closed unless the pinion carrier has attained a certain position upon its outward movement. Owing to the coaction of the faces 72 and 73, only forces tending to displace the pinion carrier outwardly can be transmitted from the iron core 20 to said pinion carrier. Moreover, the stroke of the iron core 20 is limited by a face 74 of the switch housing in such a manner, that said iron core is allowed to displace the pinion carrier into a certain position only and not to the end of its outward path.

The fly-wheel of the engine to be started by the starting device described, is designated by the numeral 75. Said fly-wheel is formed with a gear ring 76 the teeth of which, regarding pitch and shape, correspond with those of the pinion 58, when inoperative, the pinion is in the position shown in Fig. 1. To bring the pinion into engagement with the teeth of the gear ring the pinion carrier and pinion must be displaced outwards in axial direction. But the axial displacement of the pinion will not suffice under all circumstances to produce this engagement because in many cases the front faces of the teeth of the pinion will abut against the front faces of the teeth of the gear ring, and engagement can only take place when the teeth of the pinion are able to slide into the tooth gaps of the gear ring. Consequently, in the mode of operation two typical principal cases are to be distinguished, according to whether a single outward displacement of the pinion carrier suffices to bring the pinion into engagement with the gear ring or to whether it will be necessary to turn said pinion prior to effecting its engagement.

If certain conditions are assumed, in both of these cases the engagement of the pinion will take place as described hereafter. In reality, other conditions than the ones assumed might prevail in certain parts of the device so as to cause some other issue of the operation. In general, engagement of the pinion, as compared with the more unfavourable of the two cases herein-after considered, will be facilitated by these diverging conditions.

In order to start the engine by means of the starting device, the magnet coil 19 is put in circuit, for example by closing a switch in its circuit, not shown in the drawings. This coil then

attracts the iron core 20, and the peg 71 of the latter displaces the pinion carrier 55 in the engaging direction of the pinion 58 thereby compressing the spring 69. The pinion 58 which is pressed by the spring 65 against the abutting nut 61 and which, at first, encounters no resistance is also shifted in the engaging direction. Let it, for instance, be supposed that owing to their inertia, or for some other reason, the pinion carrier 55 and the pinion 58 do, at first, not rotate about their axis. The bush 37 is then turned through the steep pitch thread 56 of the pinion carrier in the operative direction 42; during this turning movement, the rotor shaft 4 carrying the armature 8 remains stationary as the overrunning clutch formed by the rollers 43 in the grooves 41 enables the bush 37 to be advanced relative to the ring 40 in the said operative direction. In this manner, the parts of the device, at first, attain the position shown in Fig. 3, in which the face of the pinion 58 has reached that of the gear ring 76.

When, contrary to the assumption made, the pinion carrier 55 and pinion 58 are rotated by a small torque while, on the other hand, the bush 37 is prevented from rotating, for example by the friction in the overrunning clutch, the pinion carrier and pinion will upon axial displacement be turned in the direction opposed to the operative direction 42 so as to assume in the axial position in which they are represented in Fig. 3 a somewhat different angular position.

The further course of the engaging operation depends on whether in the attained position of the pinion 58 each tooth of the same is opposite a tooth gap of the toothed gear ring 76 so that upon axial displacement the pinion may immediately be moved into engagement with the gear ring, or whether the face of a tooth or of several teeth of the pinion abut respectively the face or faces of a tooth or several teeth of the gear ring.

If each tooth of the pinion 58 meets a tooth gap of the gear ring 76, pinion carrier 55 and pinion 58 will be farther axially displaced by the core 20 which is attracted by the coil 19. Owing to the engagement of the teeth of pinion 58 with the still motionless gear ring 76, the pinion 58 and its carrier 55 are then forcedly prevented from rotating so that the steep pitch thread 56 of the pinion carrier compels the bush 37 to turn in the operative direction 42. The overrunning clutch formed by the rollers 43 permits the bush 37 to turn without movement of the armature of the starting motor.

When the core 20 of the electro-magnet comes in touch with the face 74 limiting its course, the parts of the starting motor will be in the position shown in Fig. 4. Immediately before reaching said position, the contact blocks 24 and 25 will come in touch with the stationary contacts 26 and 27, and during the end stroke of the core 20 the spring 22 is bent back to increase the contact pressure. The circuit of the starting motor is thereby closed and its armature begins to rotate in the direction of the arrow 42. Through the shaft 4 and the friction clutch 46—52, rotation of the armature is transmitted to the ring 40 which now tends to advance with respect to the bush 37 in the operative direction. The rollers 43 are then moved into the part of little depth of the grooves 41 so as to couple the ring 40 to the bush 37. The latter is therefore likewise driven by the armature of the starting motor.

The pinion 58 and its carrier 55 are still pre-

vented from rotating by the stationary gear ring 76; consequently, upon rotation of the bush 37, they are displaced still farther outwards in the engaging direction of the pinion. The face 73 of the shank 67 of the pinion carrier is thereby separated from the face 72 of peg 71 which is rigid with the core 20 of the electro-magnet. The spring plate 68 fast on the pinion carrier 55 finally comes in touch with the bottom 70 of bush 38; the parts are then in the position shown in Fig. 5 wherein the pinion carrier will not let itself displace any farther in axial direction.

Consequently, the torque of the bush 37, received from the armature 8 of the starting motor through the friction clutch 46—52, is transmitted from said bush to the pinion carrier 55 by the thread 56 and is also imparted to the pinion 58. The torque acting on the pinion 58 transmits to the gear ring 76 of the fly-wheel 75 a circumferential force which cranks the engine shaft and thereby sets the engine in motion.

After the engine has commenced running under its own power, it may impart to the pinion 58 a speed being higher than the speed of the armature shaft 4. This is possible without any reaction on said shaft because, on the one hand, the overrunning clutch formed by the rollers 43 permits the bush 37 to advance with respect to the ring 40 rotating with the armature speed in the operative direction. On the other hand, also the pinion carrier 55 is able to advance to a certain angle with respect to the bush 37 while being axially displaced in the disengaging direction of pinion 58. This axial displacement of the pinion carrier 55 which is likewise imparted to the pinion 58 ensues of the action of spring 69, and it is certainly limited by the face 72 of peg 71. The latter is at first in the position according to Figs. 4 and 5. But as soon as the operator has ascertained correct running of the engine, he will have to switch off the current flowing in the magnet coil 19. The pinion carrier 55 is then retracted by spring 69 into the position shown in Fig. 1 thereby shifting the magnet core 20 and peg 71 back to the initial position. The switch contacts 24/26 and 25/27 are then separated whereby the circuit of the starting motor is interrupted and the latter stopped. Also the pinion carrier 55 and pinion 58 cease to turn as soon as the latter is entirely disengaged from the gear ring 76.

Should in the position of the parts represented in Fig. 3, a tooth of pinion 58 clash against a tooth of the gear ring 76 so as to prevent said pinion from being displaced any farther in the engaging direction, the further displacement of the magnet core 20 and pinion carrier 55 will compress the spring 65 lying between said pinion carrier and the pinion shank 57. If the turning movement of the pinion 58 and hence of the pinion carrier 55 is impeded by the friction produced between said pinion and the gear ring 76, the bush 37 will be turned in the operative direction 42; that is to say the rollers 41 so that said turning movement may take place when the armature shaft 4 remains stationary. The parts then attain the position represented in Fig. 6 in which the shoulder 66 of spindle 60 abuts against the face 64 of pinion shank 57. Any farther displacement of the pinion carrier 55 and hence of the magnet core 20 in engaging direction of the pinion will then be impossible. Also the contact blocks 24 and 25 are not able to reach their stationary counter-contacts 26 and 27 re-

spectively, so that the circuit of the starting motor cannot be closed. In this way, rotation of the pinion 58 by the starting motor is prevented so long as said pinion has not been engaged with the gear ring 76.

If the operator finds that the starting motor does not commence operation, he will switch off the current of the magnet coil 19. The spring 69 then tends to displace the pinion carrier in 10 the disengaging direction of the pinion. The bush 37 being prevented by the effect of the overrunning clutch between said bush and the ring 40 from turning in opposition to the operative direction 42 when the armature shaft 4 remains 15 stationary, the pinion carrier 55 and pinion 58 are compelled by said return displacement to turn in the operative direction. During said turning movement, the friction between pinion 58 and the gear ring 76 will have to be overcome 20 by the pressure of spring 69. But owing to the slight force with which the spring 65 presses the pinion axially against the gear ring 76, the said friction is of little importance and not apt neither to impede the return of the pinion carrier 25 55 nor to produce an essential wear on the pinion 58 and the gear ring 76.

Upon this turning of the pinion 58, it may happen that the teeth of the latter arrive in front of the tooth gaps of the toothed rim. The 30 spring 65 then again displaces the pinion 58 in engaging direction so that its teeth come into engagement with those of the gear ring 76 on a small portion of their length. In this case, the pinion is prevented from turning farther and, 35 consequently, the axial return movement of the pinion carrier is interrupted. A further switching on of the magnet coil 19 then causes the pinion to be brought into the position shown in Fig. 4, and the engine may be started without further delay.

So far as the teeth of pinion 58 do not engage tooth gaps of the gear ring 76 when the pinion 58 is turned by the axial return movement of the pinion carrier 55, the pinion will finally be withdrawn from the gear ring 76 by the abutting nut 61 of the pinion carrier. The pinion carrier and pinion then continue to turn in the operative direction 42, thereby moving farther in disengaging direction so as to attain, finally, the position represented in Fig. 7 in which the bottom 63 of the pinion carrier abuts against the bottom 70 of bush 38. In Fig. 7 the pinion carrier 55 and pinion 58 are in the same axial positions as in Fig. 1 but in different angular positions, the pinion carrier which upon its axial displacement in the engaging direction of the pinion was not to be rotated having been turned upon its axial displacement in the opposite direction.

By once more switching on the magnet coil 19 60 in the starting position according to Fig. 7, the attempt to bring the pinion into engagement is repeated. On account of the new angular position of the pinion carrier and pinion, this new attempt may have a more favourable issue than 65 the unsuccessful attempt which was made in the starting position shown in Fig. 1. If not, a still other angular position of the pinion will result as new starting position for the third attempt, and so on.

The pitch of thread 56 must be so chosen that the angle through which the pinion 58 is turned at each unsuccessful operating attempt, differs from the pitch angle of the pinion and the whole multiples of said pitch angle, respectively. Experience has proved that on considering this

fact in the design, only few operating attempts are necessary in service to accomplish the engagement of the pinion 58 with the gear ring 76.

What I claim as my invention and desire to secure by Letters Patent in the United States is:

1. A starting device for internal combustion engines, the combination with a gear ring turning with the engine, of a starting motor, an axially displaceable pinion carrier, an abutment on said carrier, a pinion driven by the starting motor and adapted to be brought into engagement with said gear ring, said pinion being coupled for rotation with said carrier and axially slideable relative thereto, spring means acting upon said pinion in the engaging direction for counteracting said sliding movement and tending to press said pinion against said abutment, an intermediate member interposed between the pinion carrier and the rotor of the starting motor, coupling means connecting said rotor to said intermediate member and enabling the latter to advance relative to said rotor in the operative direction of rotation of the same, and coupling means between said member and the pinion carrier for turning said member in the said operative direction with respect to said carrier when the latter is axially displaced in engaging direction with respect to the intermediate member.

2. A starting device for internal combustion engines, the combination with a gear ring turning with the engine, of a starting motor, an axially displaceable pinion carrier, an abutment on said carrier, a pinion driven by the starting motor and adapted to be brought into engagement with said gear ring, said pinion being coupled for rotation with said carrier and axially slideable relative thereto, spring means acting upon said pinion in the engaging direction for counteracting said sliding movement and tending to press said pinion against said abutment, an intermediate member interposed between the pinion carrier and the rotor of the starting motor, an overrunning clutch coupling formed on said rotor and intermediate member, respectively, and adapted to permit said member to be advanced relative to said rotor in the operative direction of rotation of the same, and a steep-pitch thread coupling formed, respectively, on the intermediate member and the pinion carrier and active to turn said member in the said operative direction with respect to the pinion carrier when the latter is axially displaced in engaging direction with respect to the intermediate member.

3. A starting device for internal combustion engines, the combination with a gear ring turning with the engine, of a starting motor, an axially displaceable pinion carrier, an abutment on said carrier, a pinion driven by the starting motor and adapted to be brought into engagement with said gear ring, said pinion being coupled for rotation with said carrier and axially slideable relative thereto, spring means acting upon said pinion in the engaging direction for counteracting said sliding movement and tending to press said pinion against said abutment, an intermediate member interposed between the pinion carrier and the rotor of the starting motor, an overrunning clutch coupling formed on said rotor and intermediate member, respectively, and adapted to permit said member to be advanced relative to said rotor in the operative direction of rotation of the same, a steep-pitch thread coupling formed, respectively, on the intermediate member and the pinion carrier and active to turn said member in the said operative direction with respect to the pinion car-

rier when the latter is axially displaced in engaging direction with respect to the intermediate member, and a shifting member for axially displacing the pinion carrier and adapted to transmit to said carrier forces which are only effective in the engaging direction along that portion of the path of the pinion carrier through which the latter has to travel from its resting position to a position wherein the pinion engages the gear ring with at least a part of its tooth breadth.

4. A starting device for internal combustion engines, the combination with a gear ring turning with the engine, of a starting motor, an axially displaceable pinion carrier, an abutment on said carrier, a pinion driven by the starting motor and adapted to be brought into engagement with said gear ring, said pinion being coupled for rotation with said carrier and axially slideable relative thereto, spring means acting upon said pinion in the engaging direction for counteracting said sliding movement and tending to press said pinion against said abutment, an intermediate member interposed between the pinion carrier and the rotor of the starting motor, an overrunning clutch coupling formed on said rotor and intermediate member, respectively, and adapted to permit said member to be advanced relative to said rotor in the operative direction of rotation of the same, a steep-pitch thread coupling formed, respectively, on the intermediate member and the pinion carrier and active to turn said member in the said operative direction with respect to the pinion carrier when the latter is axially displaced in engaging direction with respect to the intermediate member, a shifting member for axially displacing the pinion carrier and adapted to transmit to said carrier forces which are only effective in the engaging direction along that portion of the path of the pinion carrier through which the latter has to travel from its resting position to a position wherein the pinion engages the gear ring with a part of its tooth breadth, and a switching device for the starting motor, said device being operable by the shifting member and dependent upon the movement of the pinion carrier in such a manner as to permit of starting said motor only when the pinion carrier has attained a position in which the entire axial displacement of the pinion with respect to the pinion carrier causes said pinion to engage the gear ring with at least a part of its toothed breadth.

5. A starting device as claimed in claim 1, wherein the displacement of the pinion with respect to the pinion carrier is limited also in the disengaging direction by an abutment.

6. A starting device as claimed in claim 4, wherein the displacement of the pinion with respect to the pinion carrier is limited also in the disengaging direction by an abutment.

7. In a turning gear for starting internal combustion engines, the combination of a ring gear turning with the engine; a motor having a shaft; a pinion coaxial with said shaft and axially shiftable relatively thereto to move into and out of mesh with said ring gear; a one way drive between the motor shaft and pinion comprising a member normally turning with and axially shiftable with the pinion, but shiftable axially relatively to the pinion through a limited range, a spring resisting such relative motion but adapted to yield if the pinion clashes with the ring gear, and quick pitch thread and over-running clutch means serving to cause angular displacement of the pinion relatively to the motor shaft

as an incident to the limited relative axial shift of said member in one direction; means for biasing said axially shiftable member in a direction to disengage the pinion; means for shifting said member in a direction to engage said pinion; and a controller for said motor arranged to be operated by the last named means and serving to operate the motor only after the pinion has entered meshing engagement.

8. In a turning gear for starting engines, the combination of a ring gear turning with the engine; a motor having a shaft; a pinion coaxial with said shaft and axially shiftable relatively thereto to move into and out of mesh with said ring gear; a one way drive between the motor shaft and the pinion comprising an intermediate transmitting member which normally turns with and shifts axially with the pinion, but is capable of limited axial reciprocation relatively thereto, a spring resisting such relative motion but adapted to yield if the pinion clashes with the ring gear, an over-running clutch and a quick pitch thread serially connecting the motor shaft and pinion through the intermediate member, so arranged that limited axial reciprocation of the intermediate member causes the clutch to over-run and thereby changes the angular position of the pinion relatively to the shaft; and means for shifting said intermediate member in a direction to cause the pinion to mesh with the ring gear.

9. The combination defined in claim 8 in which

the range of limited axial reciprocation and the quick pitch thread are so correlated that the change of angular position controlled thereby differs from the tooth interval of the pinion and from multiples thereof.

10. In a turning gear for starting engines, the combination of a ring gear turning with the engine; a motor having a shaft; a pinion coaxial with said shaft and axially shiftable relatively thereto to move into and out of mesh with said ring gear; a one way drive between the motor shaft and the pinion comprising an intermediate transmitting member which normally turns with and shifts axially with the pinion, but is capable of limited axial reciprocation relatively thereto, a spring resisting such relative motion but adapted to yield if the pinion clashes with the ring gear, an over-running clutch and a quick pitch thread serially connecting the motor shaft and pinion through the intermediate member, so arranged that limited axial reciprocation of the intermediate member causes the clutch to over-run and thereby changes the angular position of the pinion relatively to the shaft; means for shifting said intermediate member in a direction to cause the pinion to mesh with the ring gear; and a controller for said motor actuated by the last named means and serving to energize the motor only after meshing engagement has occurred.
